CLAIM

The ornamental design for a display screen or portion thereof with graphical user interface, as shown and described.

DESCRIPTION

FIG. 1 is a front view of an image of a display screen or portion thereof with graphical user interface, according to a first embodiment; and,

FIG. 2 is a front view of an image of a display screen or portion thereof with graphical user interface, according to a second embodiment.

The broken line showing of portions of display screens, text, and graphical elements is for the purpose of illustrating environment and forms no part of the claimed design.
